FIG. 4.

UNITED STATES PATENT OFFICE.

PETER C. HAINS, SR., OF WASHINGTON, DISTRICT OF COLUMBIA, ASSIGNEE TO AUTOMATIC CONCRETE MIXER COMPANY, OF NEW YORK, N. Y., A CORPORATION.

CONCRETE-MIXING APPARATUS.

1,051,883.

Specification of Letters Patent.

Patented Feb. 4, 1913.

Application filed June 15, 1911. Serial No. 633,383.

To all whom it may concern:

Be it known that I, PETER C. HAINS, Sr., a citizen of the United States, residing at Washington, District of Columbia, have invented certain new and useful Improvements in Concrete-Mixing Apparatus, of which the following is a full, clear, and exact specification.

This invention relates to concrete mixing apparatus of the general type shown in Letters Patent No. 633,313, dated September 19, 1899; No. 722,782, dated March 17, 1903 and No. 890,641, dated June 16, 1908 wherein concrete is prepared or mixed in a suitable receptacle in such manner that by discharging the ingredients of the mixture through a narrow aperture from the bottom of the receptacle the thorough mixing of the various materials will be effected without the necessity of agitation by hand or by mechanical means, the complete commingling of the ingredients being effected by passing them through a series of receptacles or hoppers.

The present invention aims to improve the construction particularly with reference to the door or discharge to the door or discharge of the hoppers whereby all the doors may be operated from a single point and leakage of the water prevented, thereby reducing the cost of operation and improving the quality of the product, all of which will hereinafter more fully appear.

In the accompanying drawings wherein similar reference numerals are used to indicate corresponding parts in each of the several views:—Figure 1 is an elevation of the complete apparatus, the doors of all the mixing hoppers being open, Fig. 2 is a bottom plan view of the storage bin, Fig. 3 is a bottom plan view of one of the mixing hoppers, Fig. 4 is a vertical diametrical section of the same, Figs. 5 and 6 are detail views showing the means for locking the doors of the hoppers in their closed positions.

The working platform 1 may be supported on any convenient framework which is omitted from the drawings for the sake of clearness. The platform is provided with a suitable opening in which the uppermost mixing hopper is secured and at one side of said opening a locking rail 2 is provided, said locking rail being constructed with a

plurality of notches or open ended slots 3, 55 the function of which will presently appear.

Each mixing hopper consists of an inverted conical body 4 to the upper edge of which is secured a vertical rim 5, perforated plates 6, being secured rigidly to the outer 60 side of the rim. The rim of the uppermost hopper is provided with lateral supports 7 adapted to rest upon the platform and thereby support the hopper while links or suspending rods 8 have their hooked ends 9 65 engaged in the toggle plates to thereby support the several lower hoppers. This construction permits the several links to be rapidly detached when it is desired to nest the hoppers for shipment or storage. 70

To the lower end of the hopper is secured an annular casting 10 provided with spaced lugs 11 and spaced lugs 12 diametrically opposite the same. The lugs 11 constitute means for attaching a latch but ordinarily 75 the latch will not be employed and it is therefore not shown. The lugs 12 form hinge members through which the hinge post or bolt 13 is inserted, said bolt also passing through the strap or hinge member 80 14 secured to the under side of the door 15 which forms the closure for the hopper. The door 15 is a circular plate of sufficient area to extend over the entire lower end of the hopper and is of sufficient thickness and 85 rigidity to sustain the weight of the material in the hopper and spuds 16 on the casting 10 guide the door into position to register properly with the opening in the bottom of the hopper. A staple or loop 17 is secured rigidly on the door and is engaged by the lower end of an operating rod 18 which extends through the hopper up to the operating platform. 90

The upper end of the operating rod is 95 provided with a transverse handle 19 and all the operating rods extend up to the working platform, as shown in Fig. 1. Each rod is engaged in a notch 3 in the locking rail 2 and the handle 19 will extend across 100 the notch and thereby hold it in its raised position.

To discharge the contents of the hopper it is necessary to merely release the upper end of the rod from the notch in which it 105 is engaged whereupon the door will drop and the contents of the hopper at once pass by gravity into the next lower hopper. By

this arrangement, a single workman may open and close the doors of all the hoppers and it is unnecessary to station a workman at each hopper.

- 5 From the lowermost hopper, the material passes into a storage bin 20 the bottom of which is normally closed by laterally slideable cut-offs 21 controlled by levers 22 pivotally mounted on the support for the bin 10 and secured to the cut-offs. A car or other conveyance is drawn beneath the bin and the driver or attendant on the same swings the levers to one side to permit the contents of the bin to empty into the car.
- 15 The casting 10 is formed with an annular recess in its inner face at its lower edge which receives a packing ring 23 of rubber or similar material against which is placed a steel retaining ring 24 which is secured in 20 place by screws or bolts 25 inserted through the retaining ring, the packing, and the casting. The screws or bolts will be countersunk in the ring and the ring will fit flush in the casting while the packing will project normally below the casting. When the 25 door is drawn up against the hopper, the projecting portion of the packing or elastic ring will be compressed so as to effectually seal the joint against the escape of water.
- 30 As the water cannot escape until the door is opened, it will penetrate the entire mass of material and as the doors are all operated by the same workman the liability of a 35 hopper being opened prematurely is reduced to a minimum and the mixing of the ingredients is consequently carried to the desired degree so that a superior uniform quality is imparted to the product and the cost of operation is appreciably reduced.
- 40 Having thus fully described my invention what I claim as new and desire to secure by United States Letters Patent is:
1. In a gravity concrete mixer, the combination of a hopper having an annular re-

cess in its lower edge, a downwardly opening closure for said hopper, an elastic ring seated in said recess, a retaining ring retained against said elastic ring, and means adapted to force the closure into closed position and compress said elastic ring whereby 50 a water tight joint is secured.

2. In a gravity concrete mixer, the combination of a hopper having an annular recess in its lower edge, a downwardly opening closure for said hopper, an elastic ring seated in said recess, and an operating rod for said closure adapted to draw the closure into closed position thereby compressing 55 said elastic ring whereby a water tight joint is secured. 60

3. In a gravity concrete mixer, the combination of a hopper having an annular recess in its lower edge, an elastic ring seated in said recess and projecting below the lower edge of the hopper, a retaining ring secured 65 against said elastic ring, a closure for the bottom of the hopper adapted to compress the projecting portion of the elastic ring, guiding spuds on the lower edge of the hopper, and means for operating said closure. 70

4. In a gravity concrete mixer, the combination of a hopper having an annular recess in its lower edge, a downwardly opening closure for said hopper, an elastic ring seated in said recess, a retaining ring retained against said elastic ring, and an operating rod for said closure adapted to draw the closure into closed position thereby compressing 75 said elastic ring whereby a water tight joint is secured. 80

In testimony whereof I have signed my name to this specification in the presence of two subscribing witnesses:—

PETER C. HAINS, Sr.
